(57) **CLAIM**

The ornamental design for a projectile launcher, as shown and described.

DESCRIPTION

FIG. 1 is a front/bottom/left view of a projectile launcher according to my new design;

FIG. 2 is a front/bottom/right view thereof;

FIG. 3 is a front/ top/left view thereof;

FIG. 4 is a front/top/right view thereof;

FIG. 5 is a rear/bottom/left view thereof;

FIG. 6 is a rear/bottom/right view thereof;

FIG. 7 is a rear/top/left-side view thereof;

FIG. 8 is a rear/top/right-side view thereof;

FIG. 9 is a front view thereof;

FIG. 10 is a rear view thereof;

FIG. 11 is a left view thereof;

FIG. 12 is a right view thereof;

FIG. 13 is a top view thereof; and,

FIG. 14 is a bottom view thereof.

The broken lines in the figures depict portions of the projectile launcher that form no part of the claimed design.
